UNITED STATES PATENT OFFICE

111,889

DESIGN FOR AN ADVERTISING DEVICE

Anthony John Bittson, New York, N. Y.

Application August 8, 1938, Serial No. 79,176

Term of patent 7 years

To all whom it may concern:

Be it known that I, Anthony John Bittson, a citizen of France and residing at New York, in the county of New York and State of New York, have invented a new, original, and ornamental Design for an Advertising Device, of which the following is a specification, reference being made to the accompanying drawings, forming part thereof.

Figure 1 is a view looking toward the inside of the advertising device.

Figure 2 is a view looking toward the back of the advertising device.

Figure 3 shows the advertising device partially folded.

Figure 4 shows the advertising device folded.

Figure 5 is a view showing the advertising device with the handle turned to the folding position and one side folded over.

Figure 6 is a similar view with the other side folded over.

I claim:

The ornamental design for an advertising device, substantially as shown.

A. JOHN BITTSON.
